DOORLOCK

Oscar A. Ross, New York, N. Y.

Application July 26, 1930, Serial No. 470,808

15 Claims. (Cl. 292—202)

This invention refers to locks and more particularly to that class of locks rigidly secured to control the opening and closing of doors.

One object of this invention is to furnish a lock of comparatively narrow width whereby it may be attached to the edge of wall structure or doors having small capacity transversely thereof, or to require a minimum notching of wall structure for the attachment thereto.

10 Another object is to furnish a lock wherein the opening and closing thereof is effected by a snap action from one position to the other whereby the bolt is normally restrained to remain in either the extreme open or closed position.

15 Another object is to furnish a lock of simple construction formed from metal stampings and screw machine parts whereby a low cost lock may be produced in mass production.

Another object is to furnish a lock mechanism 20 of simple form capable of being secured within hollow metal jambs of comparatively narrow form usually associated with enclosures for toilets fixtures.

Another object is to furnish a lock wherein 25 the bolt may be formed as a stamping also forming an integral portion of the bolt actuating member.

Another object is to furnish a lock having a 30 novel lock mechanism whereby the operating handle of the lock may be symmetrically located with respect to the lock housing or wall jamb to present a more ornate appearance to the exposed portions of the lock.

Other objects and advantages will appear as 35 the description of the invention progresses and the novel features are pointed out in the appended claims.

It is to be understood that divers changes may 40 be made in the structure shown by the accompanying drawings without departing from the spirit of the invention.

In describing the invention in detail reference is had to the accompanying drawings wherein 45 embodiments of the invention are illustrated and wherein like characters of reference indicate like parts throughout the several views and in which:—

Figure 1 is a part sectional, part elevational side view of one form of lock taken on line 1—1 50 of Fig. 2, and Fig. 2 is a part sectional, part elevational rear view of the same taken on line 2—2 of Fig. 1, and Fig. 3 is a bottom elevational view of the same taken on line 3—3 of Fig. 1, and Fig. 4 is a reduced size elevational view of the 55 operating side of the same lock, and Fig. 5 is a

similar view of the indicating side of the same lock, and Fig. 6 is a part sectional, part elevational view of a modified form of lock taken on line 6—6 of Fig. 7, and Fig. 7 is a rear elevational view of the same taken on line 7—7 of Fig. 6, and Fig. 8 is a fragmental sectional view of still another modified form of lock taken on line 8—8 of Fig. 9, and Fig. 9 is a fragmental rear elevational view of the same taken on line 9—9 of Fig. 8.

Referring to Figs. 1, 2, 3, 4 and 5, lock 1, comprises case or housing 2 formed by correlated positioning of angle housing member 3 and plate housing member 4, secured to wall portion 7 by bolts 6—6 engaging orifice 5—5. Diametrically disposed orifices 8 and 9 formed in members 3 and 4 are arranged to pivotally support spindle member 10 having flat sided portion 11 containing slot 12 arranged to receive the upper ends 13—13 of springs 14—14. Said spindle is also formed with shoulder 15 arranged to rotate in orifice 8 and stud portion 17 arranged to receive indicator 18. Said spindle is also formed with stud portion 19 arranged to receive handle 20 secured thereto by pin 21.

Bolt member 23 comprises upper end portion 22 rigidly secured to the flat sided portion 11 of spindle 10, the intermediate portion 25 joining said upper portion with the bolt portion 24, said member being preferably formed from a sheet 85 metal strip as an integral structure, the stop face 36 acting to limit the outward movement of bolt portion 24 and the pin 27 secured to member 3 acting to limit the inward movement thereof.

Slot 33 formed in the spindle member 30 having bearing portions 31—31 arranged to rotate in orifices 32—32 of members 3 and 4, is arranged to receive the lower ends 34—34 of spring members 14—14, said members having a resilient loop 35 formed therein.

Operation

The operation of the applicant's improved form of lock is as follows:—the strained or normally bowed position of spring members 14—14, normally act to restrain the stop portion 26 of bolt member 23 to impinge onto stop face 36 of housing member 3, as shown, this position forming the closed position of the lock, the bolt portion 24 being arranged to enter a striking plate member 37, secured to a door, or wall structure as 38. When it is desired to unlock the door, the handle 20 is manually restrained to the right to the dotted position shown in Fig. 4, this move-

85

90

95

100

105

110

ment acting to rotate spindle 10 whereby the upper end portion 13 of springs 14—14 begin to be oppositely bowed, the movement of the handle to the mid-position producing a substantially unstable condition of said springs, whereafter further movement of said handle to the right acts to inherently move said springs to the opposite bowed position as shown by the dotted lines of Fig. 1, said inherent movement acting to complete the movement of said handle to the right without manual assistance, said movement being comparatively rapid or snap acting whereby the bolt portion 24 is rapidly moved to open position and normally restrained to remain in this position until the handle is returned to its original position whereupon said bolt portion will initially move slowly and thereafter rapidly to the closed position, thereafter being resiliently restrained to remain in this position.

20 Referring to the modified form of lock 40 shown in Figs. 6 and 7, the stud 41 secured to angle member 42 is arranged to rotatably support spindle 43 having flat sided portion 44, to which is secured, preferably by welds as 45—45, the upper end portion 46 of bolt member 47, the lower end 48 thereof supporting bolt 49 arranged to travel in opening 49a.

25 Studs 50—50 rigidly secured to bolt member 47 are also rigidly secured to the upper end of spring member 51, the lower end thereof being preferably formed into a loop 52 arranged to rotate on stud 53 rigidly secured to angle housing member 42.

30 Spindle 43 is also formed with reduced size portion 19 arranged to receive operating handle 20, the washers 16a—16a acting to compensate for variation in the thickness of the wall structure to which lock 40 is attached.

35 The operation of lock 40 is similar to that described in connection with lock 1.

40 Referring to the modified form of lock 60 shown in Figs. 8 and 9, the bolt guide member 61 secured to angle housing member 62 preferably by welds as 63—63 is arranged to guide the movement of the rear end 64 of bolt supporting member 65 having bolt 66 secured thereto.

45 Stud 67, rigidly secured to bolt supporting member 65 is arranged to guide the movement of the lower end portion 68 of bolt operating member 69, said end portion moving between said stud and the angled portion 70 of bolt supporting member 65.

50 As the handle 20 is moved from one position to the other, the bolt member 71 is moved from right to left or left to right in a horizontal plane whereas the operating portion 68 of bolt operating member 69 is moved through an arc of a circle between stud 67 and angle portion 70. The operation of lock 60 includes the snap acting characteristics described in connection with the lock 1.

55 60 It is to be noted that by the novel arrangement of the resilient members as 14 and 51 in substantially a vertical plane, or longitudinally of the long dimension of the lock housings, the mechanism of the locks are confined to a comparatively small space transversely thereof, producing a slender appearing or ornate form of locks.

65 Whereas the angle members 3 and 42 and plate members 4 and 54 comprising the housing for the lock mechanism are shown as a separated housing to be attached to a building structure, said housing may form the integral portion of a hollow wall or door structure of sheet metal and the various parts of the lock mechanism inserted therein as the wall structure is initially formed, thereby further reducing the cost of said locks as

well as eliminating the cost of their attachment during the erection of the building.

What I claim is:—

1. A lock comprising a housing having a bolt opening, a bolt to move reciprocatively in the opening with reference to a keeper, an oscillating member pivotally supported in the housing to actuate said bolt into locked and unlocked positions, manually operable means on said oscillating member, said means and member being arranged to oscillate on the same axis but spaced apart along the axis, and an elongated resilient element having one end supported by said housing and the opposite end actuated by said manually operable means, the portion of said resilient member between its ends adapted to be sprung from one bowed position to an oppositely bowed position when the actuated end thereof is moved by the movement of the manually operable means. 80

2. A lock comprising a housing having a bolt opening, a bolt to oscillate in the opening with reference to a keeper, a pivotally supported bolt operating member disposed wholly within said housing to oscillate therein when moving the bolt into locked and unlocked positions, said bolt being supported by the oscillating member independently of the housing, a spindle portion on the bolt operating member extending through the housing, a manually operable member for actuating the bolt operating member supported by the spindle portion exteriorly of the housing, said members being arranged on a common axis and spaced apart therealong, and means to resiliently constrain the bolt operating means in either its locked or unlocked position. 90

3. A lock comprising a housing having side and front walls, a bolt opening in the front wall, a bolt movable inwardly and outwardly in the opening relatively to a keeper, an operating member pivotally supported by the side walls for moving the bolt in the opening, a bowed spring having the mid-portion thereof capable of inherently assuming either one of two biased positions, means supported by the side walls for pivotally supporting one end of the spring, and means rigidly securing the other end of the spring to the operating member for bodily movement thereof for moving the mid-portion to either one of the biased positions as the operating member is oscillated from one position to another. 100

4. In a lock, a housing having side and front walls, a bolt opening in the front wall, a bolt movable inwardly and outwardly in the opening relatively to a keeper, an operating member pivotally supported by the side walls for moving the bolt in the opening, a bowed spring having the mid-portion thereof capable of being sprung between two extreme bowed positions and one end thereof supported by the side walls of the housing, and means rigidly securing the other end of the spring to the operating member for bodily movement thereof for moving the mid-portion between the extreme bowed position thereof upon oscillating the operating member from one position to another. 110

5. In a lock, a housing having side and front walls, a bolt opening in the front wall, a bolt movable inwardly and outwardly of the opening relatively to a keeper, an operating member pivotally supported by the side walls, a fixed stud supported by at least one of the side walls, a bowed spring having one end supported by the stud, and the other end engaging the operating member for bodily movement thereof, the mid-portion of the spring being inherently biased for 120

130

140

145

150

- normally retaining the bolt in either one of the extreme inward or outward positions.
6. In a lock, a housing having fixed side and front walls, a bolt opening in the front wall, a bolt movable inwardly and outwardly in the opening relatively to a keeper, an operating member rigid with respect to the bolt pivotally supported by the side walls of the housing for moving the bolt inwardly and outwardly of the opening, a flat bowed spring having one end thereof supported by the housing and the other end thereof moved bodily by the operating member, the mid-portion of the spring being arranged to inherently assume either one of two extreme bowed positions upon a predetermined movement of the bodily moved end of the spring for normally retaining the bolt in either extreme inward or outward positions after movement thereof by the operating member.
7. In a lock, a housing having side and front walls, a bolt opening in the front wall, a bolt movable inwardly and outwardly of the opening relatively to a keeper, an operating member pivotally supported by the side walls of the housing for moving the bolt in the opening, a spindle pivotally supported by the side walls of the housing, a bowed spring having one end secured to the spindle and the other end secured to the operating member for bodily movement thereof.
8. In a lock, a housing having a bolt opening, a bolt in the housing having a portion movable inwardly and outwardly of the opening for engaging a keeper, a manually operated member for moving the bolt in the opening, and a bowed spring having one end supported by the housing and the other end rigidly secured to the operated member for bodily movement thereby, the mid-portion of the spring inherently assuming either one of two extreme bowed positions upon movement of the manually operated member from one position to another.
9. In a lock, a housing having a bolt opening, a bolt movable inwardly and outwardly in the opening for engaging a keeper, a manually operated member for moving the bolt between its extreme inward and outward movement, and a bowed spring having one end supported by the housing and the other end engaging the manually operated member for bodily movement thereof from one position to another, the mid-portion of the spring inherently moving from one biased bowed position to another biased bowed position upon movement of the end thereof engaging the operated member from one position to the other.
10. In a lock, a housing having a bolt opening, a fixed stud on the housing, a spindle member pivotally supported on the stud having an arm, a bolt reciprocating in the opening for engaging a keeper, the bolt being moved by the arm, a manually operated member oscillating the spindle for reciprocating the bolt, and an elongated resilient element having one end thereof supported by the housing and the other end thereof actuated by the spindle, the mid-portion of the element being inherently sprung from one biased position to an oppositely biased position as the spindle member is oscillated from one position to another.
11. In a lock, a fixed housing having a bolt opening, a bolt in the housing having a portion movable inwardly and outwardly in the bolt opening for engaging a keeper, a manually operated member pivotally supported by the housing for moving the bolt in the opening, a bowed spring having a mid-portion capable of being sprung from one biased position to another, the movement thereof being inherent during a portion of the movement thereof, means on the housing for supporting one end of the spring, means on the manually operated member supporting the other end of the spring for bodily movement thereof, the spring supporting means on the housing and the spring supporting means on the manually operated member forming the sole support for the spring between the ends thereof.
12. In a lock, a housing having a bolt opening, a bolt movable inwardly and outwardly in the opening relatively to a keeper, a manually operated member pivotally supported by the housing for moving the bolt in the opening, an elongated resilient element having one end portion supported by the housing and the other end portion rigidly secured to the manually operated member for bodily movement thereof from one position to another, a mid-portion on the element extending between the end portions and supported solely thereby, the mid-portion of the element being moved from one inherently biased position to an oppositely inherently biased position as the rigidly supported end of the element is bodily moved from one position to another by the manually operated member.
13. In a lock, a housing having a bolt opening, a bolt movable inwardly and outwardly of the opening relatively to a keeper, a manually operated member pivotally supported by the housing for moving the bolt in the opening, an elongated resilient element having one end portion supported by the housing and the other end portion actuated upon oscillation of the manually operated member, a mid-portion on the element extending between the end portions, the mid-portion of the element being inherently abruptly moved from one position to another independently of the movement of the bolt as the manually operated member is oscillated to effect movement of the bolt from one position to another.
14. In a lock, a housing having a bolt opening, a bolt movable inwardly and outwardly in the opening, a manually operated member pivoted in the housing for moving the bolt in the opening, and an elongated resilient member having one end supported in the housing and the other end actuated upon oscillation of the manually operated member, the mid-portion of the element being inherently abruptly moved from one position to another upon a predetermined oscillation of the manually operated member from one position to the other, the rate of travel of the mid-portion of the element differing from the rate of travel of the bolt as the manually operated member is oscillated from one position to the other.
15. In a lock, a housing having front and side walls, a bolt opening in the front wall, a bolt movable inwardly and outwardly in the opening, a fixed stud on one of the side walls, a manually operated member pivoted on the stud for moving the bolt, the member being pivotally supported by the stud independently of the opposite side wall, an elongated resilient member having one end supported by the same side wall supporting the stud and the other end engaging the manually operated member, the mid-portion of the spring being capable of being sprung from one biased position to an oppositely biased position as the manually operated member is oscillated from one position to the other for moving the bolt in the opening.
